SEWING MACHINE BOBBIN

James W. Lakin, Mount Holly, N.C.

Application February 21, 1955, Serial No. 34,615

Term of patent 14 years

(Cl. D70—2)

Figure 1 is an elevation of the sewing machine bobbin, illustrating the same in approximate actual size;

Figure 2 is an enlarged view similar to Figure 1;

Figure 3 is an enlarged isometric view looking at the upper portion of the bobbin;

Figure 4 is an enlarged view similar to Figure 3, but showing the other end of the bobbin.

I claim:

The ornamental design for a sewing machine bobbin, substantially as shown.
